W. C. HOLLAND

HYDROCARBON BURNER

Filed Dec. 9, 1926

Patented June 5, 1928.

UNITED STATES PATENT OFFICE.

W. CLAUDE HOLLAND, OF BEAUMONT, TEXAS.

HYDROCARBON BURNER.

Application filed December 9, 1926. Serial No. 153,557.

This invention relates to new and useful improvements in a hydrocarbon burner.

One object of the invention is to provide a burner of the character described specially 5 designed to utilize a liquid, such as oil, as a fuel and of such construction that it will completely vaporize the fuel so that the same will be completely consumed.

Another object of the invention is to provide 10 a hydrocarbon burner of the character described embodying an outwardly flared rotatable atomizing cup-like nozzle in combination with a spray head within the nozzle in fixed relation thereto, said head having 15 discharge outlets with means for supplying fuel, under pressure, to said head and with means for rotating the nozzle.

A further object of the invention resides 20 in the provision of a novel type of discharge nozzle, said nozzle being substantially cup-like in form and outwardly flared at different tapers, each taper from the inner end to the outer end of the nozzle having a greater pitch than the one preceding it.

With the above and other objects in view 25 this invention has particular relation to certain novel features of construction, operation and arrangement of parts, an example of which is given in this specification and illustrated in the accompanying drawings, wherein:

Figure 1 shows a longitudinal sectional view of the burner.

Figure 2 shows a side elevation of the 30 spray head, partly in section, and

Figure 3 shows a transverse sectional view of said head taken on the line 3-3 of Figure 2.

Referring now more particularly to the 40 drawings, wherein like numerals of reference designate similar parts in each of the figures, the numeral 1 designates the burner body, which is substantially cylindrical in form and which has an air inlet 2 controlled by 45 the inlet valve 3, which is operable through the valve lever 4, fixed to the stem 5 of the valve. The numeral 6 designates an elongated cylindrical air nozzle which is threaded into one end of the body 1 and which 50 may be formed of sections, if desired, as shown. The burner is supported by a suitable annular bracket 7, through which the air nozzle 6 extends and to which it is secured by means of a conventional clamp nut 8. The bracket 7 is provided for conveniently mounting the burner. Fixed to and

upstanding from the burner body there is the tubular connection 9 and an oil line 10 leading from a suitable source of supply has its adjacent end fitted within the connection 9 and secured therein by a suitable stuffing box arrangement 11 through which the line 10 extends and with which said line has a swivelling connection. There is a U-shaped bracket 12, one end of which is 60 formed with a suitable tubular nipple 13, which is fitted into the other end of the burner body 1 and a tubular bearing sleeve 14 has its adjacent end threaded into the nipple 13, said sleeve extending through the body 1 and into the air nozzle 6. Connected to the other end of the bracket 12 there is a reducing nipple 15 having a fuel channel 16 therethrough and the oil line 10' is connected to said reducing nipple 15 and is also connected into the connection 9 and is equipped with a shut-off valve 17. A tubular line shaft 18 is provided. This shaft extends through aligned bearings in the bracket 12 and nipple 13 and extends axially 70 through the bearing sleeve 14, being equipped with anti-friction bearings 19, 20 and 21 and fixed on said shaft, between the arms of the bracket 12, there is a pulley 22 through which said shaft may be driven in a suitable manner. Extending axially 75 through said shaft there is the oil feed line 23, one end of which is threaded into the channel 16, of the reducing nipple 15 and the other end of which extends beyond the 80 opposite end of the shaft 18. Fixed on the last mentioned end of said shaft 18 there is a cylindrical cup-like atomizing nozzle 24 which is equipped with an anti-friction bearing 25 around the adjacent end of the oil 85 feed line 23. This nozzle flares outwardly at different tapers, or flares, as shown in Figure 1, each taper from the inner to the outer end thereof, having a greater pitch or flare than the preceding taper.

Fixed to the oil feed line 23 and spaced from the nozzle 24 there is a spray head 26. This head has the internal chamber 27 and the head is preferably formed of two sections, suitably bolted together, as indicated in Figures 2 and 3. Leading out from the chamber 27 and substantially tangential thereto are the discharge outlets 28.

The fuel is forced through the line 23 into chamber 27 and out through the channels 28 against the inner wall of the nozzle 24 and the nozzle is rotated at a high rate of

speed. Upon leaving the spray head the oil will distribute itself automatically around the nozzle walls and will gradually move toward the discharge end of the nozzle and 5 will be ejected therefrom in a fog-like vapor so that it will be thoroughly atomized.

What I claim is:

1. A hydrocarbon burner including a burner body substantially cylindrical in form 10 and provided with an air inlet, an elongated cylindrical air nozzle carried by said body, a bracket formed with a nipple which is fitted into the other end of the burner body, a tubular sleeve anchored to said 15 nipple and disposed within said body, a tubular shaft extending axially through said nipple and through said sleeve, bearings in the nipple and in the free end of the sleeve in which said shaft runs, an oil line extending axially through said shaft, an atomizing nozzle within 20 said air nozzle and fixed to the adjacent end of said shaft and having a bearing on said oil line, a head fixed to said oil line within and spaced from said atomizing nozzle and formed with an internal chamber having discharge outlets leading 25 from.

2. A hydrocarbon burner including a burner body, provided with an air inlet, an elongated tubular air nozzle carried by one end of said body, a bracket having a nipple which is fitted into the other end of the burner body, a tubular sleeve anchored to 30 said nipple and disposed within said body, a tubular shaft extending axially through said nipple and through said sleeve, bearings in the nipple and in the free end of the sleeve in which said shaft runs, an oil line extending axially through said shaft, an atomizing nozzle within 35 said air nozzle and fixed to the adjacent end of said shaft and having a bearing on said oil line, a head fixed to said oil line within and spaced from said atomizing nozzle and formed with an internal chamber having discharge outlets leading 40 from.

chamber having discharge outlets leading therefrom.

3. A hydrocarbon burner including a burner body, provided with an air inlet, an elongated tubular air nozzle carried by one 50 end of said body, a bracket having a nipple which is fitted into the other end of the burner body, a tubular sleeve anchored to said nipple and disposed within said body, a tubular shaft extending axially through 55 said nipple and through said sleeve, bearings in the nipple and in the free end of the sleeve in which said shaft runs, an oil line extending axially through said shaft, an atomizing nozzle within said air nozzle and fixed to the adjacent end of said shaft and having a bearing on said oil line, a head fixed to said oil line within and spaced from said atomizing nozzle and formed with an internal 60 chamber having discharge outlets leading therefrom, and means for rotating said shaft.

4. A hydrocarbon burner including a burner body, provided with an air inlet, an elongated tubular air nozzle carried by one 65 end of said body, a bracket formed with a nipple which is fitted into the other end of the burner body, a tubular sleeve anchored to said nipple and disposed within said body, a tubular shaft extending axially through 70 said nipple and through said sleeve, bearings in the nipple and in the free end of the sleeve in which said shaft runs, an oil line extending axially through said shaft, an atomizing nozzle within said air nozzle and fixed to the adjacent end of said shaft and having a bearing on said oil line, a head fixed to said oil line within and spaced from 75 said atomizing nozzle and formed with an internal chamber having discharge outlets leading therefrom, and an oil supply line entering said shaft.

In testimony whereof I have signed my name to this specification.

W. CLAUDE HOLLAND.
